UNITED STATES PATENT OFFICE

1,992,192

EGG CARTON

John W. Cox, Chicago, Ill., assignor to Self-Locking Carton Co., Chicago, Ill., a corporation of Illinois

Application June 23, 1932, Serial No. 618,929

13 Claims. (Cl. 229—29)

The present invention relates to cellular cartons such as egg cartons, and has particular reference to an improved type of cellular carton which is easily erected.

5 Heretofore cartons have been devised which from the standpoint of carrying eggs are satisfactory. For example, Troyk Patent, No. 1,766,155, describes a cellular egg carton which has gained great favor in the art. Egg cartons are necessarily shipped from the manufacturer to the consumer in a collapsed condition and are erected or set up when it is desired to fill the carton with eggs. This problem of setting up the cartons is one which has been of particular perplexity to 10 the art for many years. To set up the carton of Troyk Patent, No. 1,766,155, it is necessary to employ a machine such as described in Burger Patent, No. 1,738,034.

20 A primary object of the present invention is to provide a carton which may be erected or set up from a collapsed condition with ease.

An additional object is to provide a novel type of collapsed cellular carton and method of making and folding the same.

25 A further object is the provision of a cushion style egg carton which may be set up by hand.

These and other objects will become apparent from a consideration of the following description and by reference to the accompanying drawings,

30 in which

Fig. 1 is a perspective view of a set-up carton made in accordance with my invention;

Fig. 2 is a perspective view of the carton shown in Fig. 1 in partially set-up condition;

35 Fig. 3 is a plan view of the carton in completely collapsed condition;

Fig. 4 is a plan view of the blank from which my carton is constructed; and

Fig. 5 is a fragmentary perspective view of a 40 modified form of my carton.

As shown in the drawings, the carton is formed by properly cutting, scoring, and folding a blank of cardboard or the like to form in the order named a cover-locking strip 1, scoring 2, cover 3, scoring 4, a rear wall 5, scoring 6, a rear bottom section 7, scoring 8, a rear longitudinal partition-forming section 9, a scoring 10, a front longitudinal partition-forming section 11, a scoring 12, a front bottom section 13, a scoring 14, a front 45 wall 15, cross partitions 16 hinged to the front wall by means of triangular hinges 17, and an attaching strip 18 hinged to the opposite sides of the cross partitions by means of similar triangular hinges 19.

50 55 The attaching strip 18 is folded over and se-

cured to the rear wall in any suitable manner, such as by gluing. Each of the longitudinal partition-forming sections is provided with a series of shoulders 20 which correspond in position with the position of the cross partitions and engage the cross partitions at the same elevation as their hinged portions. That is, the longitudinal partition sections are cut away adjacent the cross partitions to form horizontal shoulders 20 which extend from the substantially vertical stop sides 21. The stop sides 21 ordinarily are abutting the cross partitions 16 when the latter are rotated into vertical position, as shown in Fig. 1, thereby limiting the movement of the cross partitions.

5 In the modifications shown in the drawings, 15 the tops of the cross partitions are substantially level and form lines between the hinges 17 and 20 19 about which the cross partitions rotate. It will be seen that rotation of the cross partitions does not change the position of the tops of the cross partitions. It is therefore possible to secure the tops of the cross partitions beneath the horizontal shoulders 20 and adjacent the stop sides 21 and to rotate the cross partitions from a collapsed horizontal position to an erect vertical position 25 without damage to the elements and without removing the cross partitions from engagement with the shoulders 20.

To allow rotation of the cross partitions the longitudinal partition-forming sections are cut 30 away in front of the shoulders 20, as shown at 22, and the cross partitions are provided with slots 23 which receive the sections 8 and 11. As shown in the drawings, the cut-away portions 22 are 35 arcuate in form and have centers coincident with the tops of the cross partitions.

The slots 23 have an additional important function in receiving the sections 8 and 11 and preventing their outward movement. The bottom sections 7 and 13 are not joined adjacent 40 the scorings 8 and 12, and the carton therefore has a tendency to spread apart into a collapsed condition. When the cross partitions are rotated into vertical position the slots 23 securely hold the sections 9 and 11 and thereby maintain the 45 carton erected. The upper parts of the cut-away portions 22 are substantially vertical above the top of the cross partitions.

In addition to arranging the cross partitions and the longitudinal partitions in such a manner 50 as to permit the cross partitions to be rotated while in engagement with the longitudinal partitions, I have provided a means whereby the carton may be collapsed by a simple movement.

The front wall of the carton is of less height 55

than the rear wall, and the attaching strip 18 is glued to the rear wall at a height equal to that of the front wall. The cross partitions are made twice as wide as the front wall. The bottom sections, including the longitudinal partition sections, are of a width equal to the width of the cross partitions plus twice the width of the front wall. As shown, each of the bottom sections is equal in width to the width of the front wall, as 10 is each of the longitudinal partition sections. The relation of the parts may be expressed by the equation:

$$7+9+11+13=16+2 \times 15$$

- 15 In order to provide the carton with a cushion bottom, the front wall is made lower than the rear wall, and the shoulders 20 are substantially of the same height as the difference in height of the front and rear walls. As the longitudinal partition sections are of the same height or width as the front wall, suspension of the shoulders 20 to the top of the cross partitions causes the bottom sections 7 and 13 to assume an inverted V-shape when the carton is erected.
- 20 25 As the end cross partitions of cartons of the type shown in Fig. 1 have a tendency to be loosened, it is desirable to provide a carton as shown in Fig. 5, wherein both end shoulders are faced inwardly. This results in two shoulders adjacent 30 one end, facing in opposite directions. To collapse the carton shown in Fig. 5, the cross partition 24 is placed in a horizontal position and the end cross partition 25 is rotated inwardly an additional 90° so that it rests beneath and in contact with the partition 24. The longitudinal partition sections are provided with two complementary cut-away portions 22 between the partitions 24 and 25. By providing a carton of this structure the carton may be collapsed while the 35 cross partitions are in horizontal position by folding along the scoring 6 between the rear wall and the rear bottom section and the scoring 14 between the front wall and the front bottom section. When this is done the top and cover-locking strip extend horizontally over the cross partitions and terminate short of the scoring 14. In 40 Fig. 3, the cover and locking strip are shown in vertical position so as not to obscure other parts of the carton.
- 45 50 As shown in Fig. 3, the shoulders 20 are in flattened condition but still overhang the top of the cross partitions.

To set up or erect the carton from the condition shown in Fig. 3, it is necessary only to press the 55 carton inwardly along the extended edges formed by the scorings 6 and 14. This movement causes the carton walls to be distended toward erect position, as shown in Fig. 2. As the pressure along scorings 6 and 14 is continued the carton 60 is caused to bend along the scorings 8, 10, and 12, and along the outer edges of the triangular hinges 17 and 19 by which the cross partitions are secured to the front and rear walls. The front and rear longitudinal partition-forming 65 sections 9 and 11 approach each other as the movement is continued, and when these sections are in substantially the position shown in Fig. 1, the cross partitions are rotated into erect position, thereby causing the slots 23 to engage the 70 sections 9 and 11 maintain the carton in erected condition. Any suitable means may be employed for rotating the cross partitions into erect condition. I have found it to be convenient to rotate 75 the partitions into erect position by the same

movement with which an egg is inserted in the cells of the carton.

In manufacture, a blank such as shown in Fig. 4 is prepared by suitably cutting and scoring a sheet of cardboard or other material. The blank is then folded about the scoring 14 and the tops of the cross partitions are inserted beneath the shoulders 20, it being understood that the parts are flexed sufficiently to permit the cross partitions to pass beneath the front edge of the shoulders. The attaching strip is supplied with glue, and the rear wall is pressed against the glued attaching strip by bending the blank along the scoring 6.

It will be seen that I have provided a cushion style carton which is composed of a single piece of material and which may be easily and quickly erected without the application of any mechanical device whatever. The cartons are shipped collapsed, as shown in Fig. 3. A worker can erect the cartons by merely holding one edge and striking the other edge against some object, whereby the walls of the carton are distended. The cross partitions are rotated into position by the same movement by which eggs are inserted in the carton. Mechanical devices such as blocks or projections may be employed if desired to rotate the cross partitions into erect position. In fact, the carton may be completely erected by machinery with very little difficulty, due to the simplicity of the movements necessary to erect the carton.

In order to facilitate the erection of the carton, it is desirable to make the scorings somewhat heavy, and in certain cases, particularly where a heavy or stiff grade of paper is employed, it will be advantageous to provide spaced cuts along 35 scorings 8 and 11.

The various modifications of the structure and methods described herein for purposes of illustration and explanation which come within the spirit of my invention are intended to be included 40 in the appended claims.

I claim:

1. A carton comprising a blank cut, scored and folded to form, in the order named, a rear wall, a first bottom section, a first longitudinal partition section, a second bottom section, said bottom sections being in inverted V-shape when the carton is erected, a front wall, cross partitions hinged to said front wall, and a gluing strip hinged to 50 said cross partitions and folded over and secured to the rear wall at a height corresponding to the height of the front wall, said longitudinal partition sections having shoulders engaging said cross partitions at the same elevation as the hinged 55 portions of said cross partitions.

2. A carton, comprising a blank cut, scored and folded to form a rear wall, a rear bottom section, a rear longitudinal partition section, a front longitudinal partition section, a front bottom section, a front wall, cross partitions hinged to said front wall, and a gluing strip hinged to the opposite sides of said cross partitions and folded over and secured to said rear wall, said longitudinal partition sections having shoulders 60 engaging said cross partitions at the same elevation as the hinged portions of said cross partitions, and the width of the rear wall below the cross partitions, said cross partitions and said front wall being equal to the width of said bottom sections and said longitudinal partition sections 65 said bottom sections being suspended in inverted V-shape when the carton is erected.

3. A carton, comprising a blank cut, scored and folded to form a rear wall, a rear bottom section, 70

a rear longitudinal portion section, a front longitudinal partition section, a front bottom section, a front wall, cross partitions hinged to said front wall, an attaching strip hinged to the opposite sides of said cross partitions and folded over and secured to the rear wall at a height equal to the height of said front wall, said longitudinal partitions having shoulders engaging the tops of said cross partitions at a height equal to the height of the front wall, the height of said longitudinal partitions below said shoulders being less than the height of said front wall, whereby to suspend said bottom sections in inverted V-shape, and the width of said bottom sections and said longitudinal partition sections being equal to the width of said cross partitions plus twice the width of said front wall.

4. A carton, comprising a blank cut, scored and folded to form a cover, a rear wall, a rear bottom section, a rear longitudinal partition section, a front wall of less height than said rear wall, cross partitions hinged to the top of said front wall, an attaching strip hinged to the opposite sides of said cross partitions and folded over and secured to the rear wall at a height equal to the height of the front wall, the widths of said front wall and each of said bottom sections and said longitudinal partition sections being equal, the width of said cross partitions being twice that of said front wall, and said longitudinal partition sections having shoulders engaging said cross partitions at a height equal to the height of said front wall, said shoulders being sufficiently wide to suspend said bottom sections in inverted V-shape, said shoulders extending upwardly to form a brace for said cover.

5. A carton having front and rear walls, cross partitions hinged to said walls, cushion-forming bottom sections including longitudinal partition sections provided with shoulders engaging said cross partitions on the level of the hinges of said cross partitions, said carton being folded in collapsed condition along the bottom edges of said front and rear walls.

6. A carton comprising a blank cut, scored and folded to form front and rear walls, cross partitions hinged to said walls, and cushion-forming bottom sections including longitudinal partition sections having shoulders engaging said cross partitions at the elevation of their hinged portions, said longitudinal partition sections being cut away in front of said shoulders to permit said cross partitions to be rotated downwardly into erect position.

7. A carton, comprising a blank cut, scored and folded to form front and rear walls, cross partitions hinged to said front and rear walls at the elevation of said front wall, said cross partitions being twice as wide as said front wall, and cushion-forming bottom sections including longitudinal partition sections having shoulders engaging said cross partition sections at the elevation of their hinged portions, said bottom sections being four times as wide as said front wall, and said longitudinal partition sections being cut away in front of said shoulders to permit said cross partitions to be rotated downwardly into erect position.

8. A carton, comprising a blank cut, scored and folded to form front and rear walls, cross partitions hinged to said walls, and cushion-forming bottom sections including longitudinal partition sections having shoulders engaging said cross partitions at the elevation of their hinged portions, the shoulders adjacent the end cross parti-

tions being both faced inwardly, and said longitudinal partition sections being cut away in front of each of the shoulders thereon to permit said cross partitions to be rotated into erect position.

9. A carton, comprising a blank cut, scored and folded to form front and rear walls, cross partitions hinged to said walls at the elevation of said front wall, said cross partitions being twice as wide as said front wall, and cushion-forming bottom sections four times as wide as said front wall and including longitudinal partition sections having shoulders engaging said cross partitions at the elevation of their hinged portions, the shoulders adjacent the end cross partitions being both faced inwardly, and said longitudinal partition sections being cut away in front of each of the shoulders thereon to permit said cross partitions to be rotated downwardly into erect position.

10. A carton composed of a plurality of sections each separated by a scoring and comprising a rear wall, a rear bottom section, a rear longitudinal partition section, a front longitudinal partition section, a front bottom section, a front wall, cross partitions hinged to the front wall, an attaching strip hinged to said cross partitions and secured to the rear wall, said longitudinal partition sections having shoulders engaging said cross partitions at the elevation of their hinged portions and suspending said bottom sections above a surface upon which said carton is placed, said bottom sections being equal in width to said cross partitions plus twice the width of said front wall and having an inverted V-shape when the carton is set up.

11. A carton having front and rear walls of substantially plane shape and extending downwardly to a surface upon which the carton is positioned, cross partitions hinged to the upper portion of the front wall and to the rear wall, said cross partitions lying in a horizontal position when in collapsed condition and being rotatable into erect position, and a bottom section of substantially inverted V-shape and provided with an upwardly extendable longitudinal partition, the width of said bottom section being equal to the width of said cross partitions plus the width of said front and rear walls below the points at which said cross partitions are hinged thereto.

12. A carton, comprising a blank cut, scored and folded to form a rear wall, a rear bottom section, a rear longitudinal partition section, a front longitudinal partition section, a front bottom section, a front wall, and cross partitions hinged to the upper portions of said front and rear walls and being rotatable from a horizontal collapsed position into erect position, the width of said cross partitions plus the widths of said front and rear walls below the points at which said cross partitions are hinged thereto being equal to the widths of said bottom sections plus the widths of said longitudinal partition sections, the front and rear walls being of substantially plane shape and extending downwardly to the surface upon which the carton is positioned, and the rear bottom sections being connected to the lower edges of said front and rear walls and extending upwardly therefrom to the center of the carton in substantially inverted V-shape.

13. A carton, comprising a blank cut, scored and folded to form front and rear walls of substantially plane shape and extending downwardly to the surface upon which the carton is positioned, a cover joined to the upper edge of said rear wall, cross partitions hinged to said walls

and rotatable into erect position with respect to said walls, front and rear bottom sections being inclined upwardly in substantially inverted V-shape to meet at a point adjacent the center of the carton, longitudinal partition sections extending vertically in contiguous relation from said bottom sections to a position in contact with and forming a brace for said cover, said longitudinal partition sections having slots for receiving cross

partitions, and interlocking means on said longitudinal partition sections and said cross partitions, the width of said cross partitions plus the widths of said front and rear walls below the points at which said cross partitions are hinged thereto being equal to the widths of said bottom sections plus the widths of said longitudinal partition sections.

JOHN W. COX.
